US00D820690S

(12) United States Design Patent (10) Patent No.: US D820,690 S
(45) Date of Patent: * Jun. 19, 2018

(54) BOX

(71) Applicant: SOREMARTEC S.A., Rue de Treves (LU)

(72) Inventor: Franco Canuto, Raca di Guarone (IT)

(73) Assignee: SOREMARTEC S.A., Findel (LU)

() Term: 15 Years

(21) Appl. No.: 29/596,456

(22) Filed: Mar. 8, 2017

Related U.S. Application Data

(63) Continuation of application No. 29/503,221, filed on Sep. 24, 2014.

(30) Foreign Application Priority Data

Mar. 28, 2014 (WO) 803347501

(51) LOC (11) Cl. 09-03

(52) U.S. Cl.

USPC D9/757; D9/737

(58) Field of Classification Search

USPC D9/737, 756, 757, 761, 762, 414, 418, D9/420, 424, 430, 432, 643, 647; D7/601, 602, 611, 701, 703, 708; D3/273, 294, 295, 315; D11/143, 155, D11/156; 206/769, 459.5, 561; 40/661; 426/128

(57) CLAIM

The ornamental design for a box, as shown and described.

DESCRIPTION

FIG. 1 shows a top plan view of the box;

FIG. 2 shows a bottom plan view thereof;

FIG. 3 shows a right side elevation view thereof;

FIG. 4 shows a left side elevation view thereof;

FIG. 5 shows a front elevation view thereof;

FIG. 6 shows a rear elevation view thereof; and,

FIG. 7 shows a perspective view thereof.

1 Claim, 6 Drawing Sheets
